IRA S. DOWNING, OF CLEVELAND, OHIO.

COUPLING-CENTERING DEVICE FOR RAILWAY-CARS.

1,112,897.

Specification of Letters Patent.

Patented Oct. 6, 1914.

Application filed September 26, 1912. Serial No. 722,451.

To all whom it may concern:

Be it known that I, IRA S. DOWNING, a citizen of the United States, residing at Cleveland, in the county of Cuyahoga and State of Ohio, have invented certain new and useful Improvements in Coupler-Centering Devices for Railway-Cars, of which the following is a specification.

This invention has reference particularly to an improved form of mechanism for centering the coupling of a railway car, such mechanism being so constructed as to provide for disconnecting—that is, temporarily or manually throwing out of gear—the centering means in order to permit a shift of the coupler laterally to a position which will facilitate coupling on a curve. A further object of the invention is to provide means whereby the centering mechanism will automatically return to operative position after it has been thrown out temporarily by manual action.

Still another object of this invention is the provision of an improved apparatus of the character specified, in which the device proper which centers the coupler is supported from the coupler shaft in preference to the arrangement usually employed in which all of the mechanism of this character is attached to the carry iron, and in many instances is in the way of the operating devices arranged to manipulate the lock of the coupler; especially where such devices are located underneath the coupler shank.

The above, as well as such other objects as may hereinafter appear, I attain by means of a construction which I have illustrated in preferred form in the accompanying drawing wherein—

Figure 1 shows a plan view of a coupler with my improvement applied thereto; Fig. 2 is a view partly in section, the section being taken on the line II—II of Fig. 1; Fig. 3 is a side elevation of the device, with a portion of the centering mechanism shown in section; Fig. 4 indicates the relative action or movement of the parts when the centering device is in operative position, and the coupler is forced to one side of the center line; Fig. 5 is a view partly in section, of the housing or casing which contains the centering spring, and Fig. 6 is another view

of the apparatus shown in Fig. 5 and indicates also the means which I preferably employ for supporting the housing from the coupler shank.

Referring now more particularly to Figures 1, 3, and 4, it will be seen that I have therein illustrated a coupler having a head 7 attached to the shank 8 secured to the bars 9 arranged to swing from the pivot 10. Underneath the shank 8 is arranged a housing or casing 11 secured by means of a strap 12 in the manner shown in Figure 6, and adapted to contain a centering spring 13 which when under compression can be put into the housing from one side, and is so disposed when in place as to bear against the wall 14 at one end, and against the washer or block 15 at the other end which has a rounded nose or projection 16 seated in a socket piece 17 that forms an upstanding part of the longitudinally extended arm or lever 18 which reaches outward in the direction of the coupler head as clearly shown in Figure 4, and is adapted to be held in a recess or socket formed in the two projecting lugs 19 and 20 that are secured to the carry iron 21.

The carry iron as indicated in Figure 2 is made sufficiently wide to permit the coupler bar 8 to swing from one side to the other a sufficient distance to provide for all necessary coupling actions or movements of the cars, while the arm or lever 18 being held between the lugs 19 and 20 will resist the lateral movement of the coupler bar and coupler head through compression of the spring 13, due to the peculiar bell crank lever which has the bearings at 22 and 23 arranged to abut against the round surfaces of the casing at 24.

Through the center of the spring and the washer 15, and bracket projection 17 of the arm 18, there is extended a bolt 25 which serves to hold the several parts in proper relation or against displacement.

The operation of my device is as follows: The parts normally being in the position shown in Figures 1 and 3, with the lever 18 seated in the recess between the abutting members 19 and 20, it is evident that if the coupler head is moved laterally either side from the center line as indicated in Figure 4,

the parts will assume the position shown in such Figure 4, and the bell crank construction of the lever 18 by abutment of the surfaces at 22 and 24 will exert a compression upon the spring 13, such as will tend to immediately return the coupler to central position as soon as the lateral strain is removed.

If now the car be standing on a curve and it be desired to make a coupling connection with another car upon the curve, and to facilitate this operation the coupler head is thrown to one side of the center, this action can be accomplished without the necessity of overcoming the heavy lateral resistance exerted by the spring 13, by merely pushing the lever 18 down out of engagement with the lugs 19 and 20, which can be readily done as will be clear from an examination of Figure 3, by inserting a stick of wood or 20 brake bar such as the brakeman ordinarily carries, between the projecting end of the lever marked 18^a and the under face of the coupler shank and prying down upon the lever 18, moving the coupler head a little 25 to one side as soon as the lever 18 is out of engagement with the lugs 19 and 20, when the lever 18 will ride along on the under face of the said lugs or either of them, and follow the line of movement of the coupler 7 30 without material resistance, all the parts remaining, however, in proper position so that as soon as the coupler head returns to central position the lever 18 will again become engaged with the projections or lugs 19 and 20 35 as before, and take up again its automatic action in centering the coupler device.

It will be observed that the amount of force necessary to push down the lever 18 in the manner just described is not great, because it swings about the point 26 indicated in Figure 3 as a center, and has a greater leverage upon the spring 13 than the end of the lever 18 has against the spring 13 as opposed to lateral or centering movement.

45 Various other types of springs may be employed between the shank and its lever, and other locking means for the lever might be substituted for the one shown without departing from the invention.

50 It will further be observed that the operative parts of my mechanism are located sufficiently far inward from the end of the coupler so as not to interfere with any mechanism that may be applied for actuating the coupler locking device from the under side, and also to be out of the way of other devices that may be used on the end of the car, and the position of the apparatus is also such that it can be readily supported by the carrying strap or bolt 12, and is compact, easy to apply, accessible for purpose of repair, and in position where it is not liable to be injured while in use.

Having thus described my invention and 55 illustrated its use, what I claim as new and

desire to secure by Letters Patent, is the following:

1. In combination in a car coupler, a coupler head, a shank therefor mounted for swinging movement, a carry member over which the shank moves, locking means carried centrally upon the lower side of the said member, a lever pivotally mounted upon the lower side of the shank, and spring means tending to hold the lever in 75 parallelism with the shank, the free end of the lever having releasable engagement with the said locking means.

2. In combination in a car coupler, a coupler head, a shank therefor mounted for 80 swinging movement, a carry member over which the shank moves, locking means carried centrally upon the lower side of the said member, a lever pivotally mounted upon the lower side of the shank, and spring means tending to hold the lever in parallelism with the shank and pressing the lever yieldingly against the under side of the carry member, the said locking means comprising means projecting downward from 90 the carry member and adapted to prevent lateral movement of the end of the lever.

3. In combination in a car coupler, a coupler head, a shank therefor mounted for swinging movement, a carry member over 95 which the shank moves, locking means carried centrally upon the lower side of the said member, a lever pivotally mounted upon the lower side of the shank, and spring means tending to hold the lever in parallelism with the shank and pressing the lever yieldingly against the under side of the carry member, the said locking means comprising a pair of projections spaced apart 100 to receive the lever between them and having inclined faces.

4. In combination in a car coupler, a coupler head, a shank therefor mounted for lateral swinging movement, a carry iron 110 over which the shank moves, locking means beneath the carry iron, and a lever pivotally mounted upon the lower side of the shank, with its free end in releasable engagement with the said locking means and freely movable with the shank when the engagement with the locking means is released, and spring means between the lever and shank tending to hold the shank in its central position when the lever is in engagement with the locking means.

5. In combination in a car coupler, a coupler head provided with a shank pivoted at its rear end to permit lateral swinging movement of the head and shank, a carry iron upon which the shank is slidably supported adjacent the head, a lever pivotally supported at its rear end upon the lower side of the shank and with its front end beneath the carry iron, locking means carried on the lower side of the carry iron and adapted to 130

automatically engage the said free end of the lever when the shank reaches its central position and spring means between the lever and shank tending to hold the shank in central position when the lever is engaged by the said locking means.

In testimony whereof I have hereunto

signed my name in the presence of the two
subscribed witnesses.

IRA S. DOWNING.
